No. 772,105.

PATENTED OCT. 11, 1904.

B. F. LACY.

ABDOMINAL SUPPORTER AND TRUSS.

APPLICATION FILED FEB. 15, 1904.

NO MODEL.

UNITED STATES PATENT OFFICE.

BENJAMIN F. LACY, OF PEKIN, ILLINOIS.

ABDOMINAL SUPPORTER AND TRUSS.

SPECIFICATION forming part of Letters Patent No. 772,105, dated October 11, 1904.

Application filed February 15, 1904. Serial No. 193,595. (No model.)

To all whom it may concern:

Be it known that I, BENJAMIN F. LACY, a citizen of the United States, residing at Pekin, in the county of Tazewell and State of Illinois, 5 have invented certain new and useful Improvements in Abdominal Supporters and Trusses, of which the following is a specification.

This invention relates to an improved surgical appliance designed to perform the dual 10 function of a bandage or abdominal supporter and also of a truss for the retention of hernia or rupture.

To this end the invention has specially in view the provision of a simple, practical, and 15 effective form of supporter and truss so constructed as to fit the abdomen with perfect comfort to the wearer and at the same time adapt it to hold the outer abdominal wall in such a manner as to promote the knitting of 20 the inner membrane to the outer wall at the edge of the broken ligaments, thus providing the only conditions under which a hernia or rupture can be cured.

In the above connection the invention provides 25 a supporter which depresses the entire abdominal cavity and at the same time embodies means whereby it is held secure against displacement from the position in which it may be fitted.

With these and many other objects, which 30 will more readily appear as the nature of the invention is better understood, the same consists in the novel construction, combination, and arrangement of parts, which will be hereinafter more fully described, illustrated, and claimed.

The essential feature of the invention involved in the novel formation of the supporter-frame to constitute an abdominal bandage or 35 supporter and also a truss for the retention of hernia is necessarily susceptible to structural modification without departing from the scope of the invention; but a preferred embodiment of the latter is shown in the accompanying 40 drawings, in which—

Figure 1 is a front elevation of an abdominal supporter and truss embodying the present invention and shown in its applied position upon the body of a person. Fig. 2 is a detail 45 perspective view of the supporter and truss

proper, showing the protective fabric casing partly broken away to expose the spring-wire supporter-frame. Fig. 3 is an elevation of the spring-wire supporter-frame, illustrating a modification wherein the frame is bent specially for adaptation to a direct inguinal hernia. Fig. 4 is a detail view showing a modification wherein a separate pad is applied to the supporter-frame.

Like numerals designate corresponding 60 parts in the several figures of the drawings.

In carrying out the invention the same primarily involves a spring-wire supporter-frame designated in its entirety by the numeral 1 and made from a continuous length of brass 65 spring-wire of suitable strength and gage. The wire from which the frame is made can be bent into shape through the medium of any suitable instrumentalities without affecting the structural features of the invention, as in all 70 cases the wire is bent into an arched or U-shaped form, as plainly shown in the several figures of the drawings. This arched or U-shaped-spring supporter-frame is designed to be arranged in an upright position over the 75 abdominal cavity and wholly at the front side of the body, whereby the frame when drawn with proper pressure upon and against the body serves to depress the entire abdominal cavity, and thereby bring into close relation 80 the broken ligaments surrounding the hernia or rupture, thereby placing the parts in condition for healing by natural process.

The wire constituting the arched or U-shaped supporter-frame is bent so as to extend directly over and beneath the hernia or rupture, and thus ordinarily constitutes a pad member itself for retaining the hernia in place, and in ordinary cases of bubonocele rupture 85 the side portions of the frame are provided with suitable deflections constituting retaining-bends 2 for holding the rupture. However, in case the rupture is very large there 90 may be placed directly on the sides of the frame at these points a separate metallic or 95 equivalent pad 3, such as shown in Fig. 4 of the drawings, and which could be placed on the wire before the supporter or truss frame is bent up into shape. Also in case of rupture in other places the retaining bends or pads could 100

be placed at those points—such, for instance, as suggested in Fig. 3—wherein the bottom portion of the supporter-frame is shown provided with downwardly-extending retaining 5 bends or offsets 2^a, designed for holding an inguinal hernia.

In all embodiments of the invention the spring-wire supporter-frame 1 is provided at the opposite upper ends thereof with the 10 spring-coils 4, and the terminals of the wire at these points are extended downwardly and outwardly from the coils to provide the spring-lever arms 5, having hooked terminals or eyes 6, to which are connected the front extremities 15 of an adjustable body-band 7, passing around the hips and the back of the body and tightened to any desired degree, according to the pressure with which the frame is to be held over the abdomen. In the case of inguinal hernia the lever-arms 5 are made longer, as shown in Fig. 3, whereby a stronger 20 pressure may be provided at the lower part of the truss. Also in carrying out the invention the upper ends of the frame are designed 25 to be connected by an adjustable front supporting-belt 8, which may be manipulated to fit the frame or truss and which also provides a means for holding an umbilical rupture. This may be assisted by attaching an umbilical 30 pad 9 directly to the belt or band 8, as suggested in Fig. 2.

The entire metallic spring-wire frame 1, except its lever-arms 5, is designed to be received within the pocket of a protective fabric casing 10, which forms the contact-surface 35 for the body.

Various changes in the form, proportion, and minor details of construction may be re-

sorted to without departing from the spirit of the invention or sacrificing any of the advantages thereof. 40

Having thus described the invention, what is claimed, and desired to be secured by Letters Patent, is—

1. In a device of the class described, a U-shaped spring-wire supporter-frame having rupture-retaining means and provided at its ends with lever-arms, a body-band connected to the terminals of the lever-arms, a transverse holding-band connected at its ends to the ends of the U-shaped frame and arranged in front of the body, and a casing receiving the U-shaped frame. 45

2. In a device of the class described, a U-shaped spring-wire supporter-frame provided at its ends with spring-coils and outwardly-deflected lever-arm extensions projected from said coils, a transverse holding-band connected at its ends to the spring-coils and arranged in front of the body, and an adjustable body-band encircling the body and connected at its front ends with the terminals of the lever-arm extension. 55

3. In a device of the class described, an upright U-shaped spring-wire supporter-frame having rupture-retaining bends, an umbilical rupture-holding band connecting the ends of the frame in front of the body, and supporting means for holding the frame upon the abdomen. 60

In testimony whereof I affix my signature in presence of two witnesses.

BENJAMIN F. LACY.
